UNITED STATES PATENT OFFICE.

LAWRENCE W. GUSTAFSON, OF SMOLAN, KANSAS.

COMB-HOLDER.

1,284,320.

Specification of Letters Patent. Patented Nov. 12, 1918.

Application filed January 24, 1917. Serial No. 144,256.

To all whom it may concern:

Be it known that I, LAWRENCE W. GUSTAFSON, a citizen of the United States, residing at Smolan, in the county of Saline and 5 State of Kansas, have invented certain new and useful Improvements in Comb-Holders, of which the following is a specification.

This invention relates to an improved comb holder and the principal object of the 10 invention is to provide a comb holder so constructed that it may be held in the pocket and to further provide an improved type of securing clip adjustably mounted so that the comb holder may be held extended above 15 the upper edge of the pocket a desired distance thus permitting the holder to be easily reached and further permitting the holder to be slid in the pocket if so desired.

This invention is illustrated in the accompanying drawings, wherein:—

Figure 1 is a view in front elevation showing the improved comb holder in place.

Fig. 2 is a vertical sectional view through the comb holder taken along the line 2—2 25 of Fig. 1.

Fig. 3 is a transverse sectional view through the comb holder taken along the line 3—3 of Fig. 1.

The comb holder 10 is in the form of a 30 receptacle formed of leather or any suitable material and of sufficient size to hold the comb 11 with the upper end of the comb extending slightly from the open end of the holder.

35 The securing means for the holder comprises the base 15 which is provided with

overhanging flanges 16 forming a track for the reception of the base portion 17 of the engaging hook 18. When this form is in use, the securing or clamping tongue 18 may be 40 adjusted upon the base or track and the case can be held extended above the upper edge of the pocket a desired extent. It will also be possible to draw the case out of the pocket and then withdraw the comb and after using 45 the comb, insert the comb in the case and push the case down into the pocket. This would provide a very convenient case as the comb could be easily removed from the same and at the same time, the case could be ad- 50 justed in the pocket.

I have thus provided a comb holding case which is so constructed that it may be placed in the pocket without danger of dropping out when leaning over.

55 What is claimed is:—

A comb holder comprising a casing, a base plate extending longitudinally of said casing, spaced guide strips extending along the length of said plate, inwardly directed 60 flanges formed on said guide strips, a sliding plate engaging said base plate and fitted between said guide strips, and a clamping arm integral with one end of said sliding plate and reversely curved to extend beyond 65 the opposite end thereof.

In testimony whereof I affix my signature in presence of two witnesses.

LAWRENCE W. GUSTAFSON.

Witnesses:

FRED HEDERSTEDT,

GLENN BERGSTEN.
